UNITED STATES PATENT OFFICE.

WALTER B. BALLOU, OF NORTH ATTLEBORO, MASSACHUSETTS, ASSIGNOR TO E. BLACKINTON & CO., OF NORTH ATTLEBORO, MASSACHUSETTS.

BELT-BUCKLE.

1,183,425.

Specification of Letters Patent. Patented May 16, 1916.

Application filed December 17, 1915. Serial No. 67,339.

To all whom it may concern:

Be it known that I, WALTER B. BALLOU, a citizen of the United States, residing at North Attleboro, in the county of Bristol and State of Massachusetts, have invented a new and useful Improvement in Belt-Buckles, of which the following is a specification.

This invention relates to certain new and useful improvements in belt buckles and the primary object thereof is to provide a buckle in which the bail may be applied after the buckle body has been polished and finished, and also wherein the gripping roller ¹⁰ may be removed and applied at will, particularly for the purpose of piercing the front face of the buckle with a monogram or other ornamentation.

In the drawings—Figure 1 is a perspective view of the invention. Fig. 2 is a rear plan view. Fig. 3 is a section on the line 3—3 of Fig. 2, and Fig. 4 is a similar view on the line 4—4 of Fig. 3.

The belt buckle has a body 1 with side flanges 2 the latter formed with inclined slots 3. The roller has a hollow cylindrical body 4 corrugated peripherally so as to effectively grip the leather belt, and is secured to the body by means of pins having tapered ends 5 which have a frictional drive into the ends of roller body 4 and have heads 6 which engage over the flanges 2. These pins have sufficient frictional engagement with the walls of the bore of roller 4 so as to effectively secure the roller in position. The bail 7 has cranked ends 8 which latter are passed through openings provided therefor in the flanges 2 and are headed at 9 by the usual process common to riveting, subsequent to the ends 8 being passed through

the openings provided therefor. It will be apparent that the cranked ends of the bail permit the latter to be easily passed through the flange openings provided therefor, by slightly springing the flanges apart or outwardly, which enables the bail to be inserted after the buckle body has been completely polished and finished. Similarly the roller may be easily removed at any desired time for the purpose of either piercing the body or any other reason. This final securing of the bail after the article has been polished is important since with its presence during polishing the latter operation would be awkward, tedious and time consuming, if not preventing perfect finish and polish being imparted to the buckle body.

Having thus described my invention, what I claim as new and desire to secure by Letters Patent is—

1. In a belt buckle, a body having side flanges provided with inclined slots and with openings, a bail having cranked ends passed through the openings and subsequently headed, and a hollow roller having tapered headed pins driven thereinto through the slots.

2. In a belt buckle, a body having flanges with inclined slots, a roller between the flanges, and pins driven into the ends of the roller so as to permit removal of the same, the pins extending through the slots.

In testimony whereof I have signed my name to this specification in the presence of two subscribing witnesses.

WALTER B. BALLOU.
